UNITED STATES PATENT OFFICE

JOHN E. LAIRD, OF MATAWAN, NEW JERSEY

DESIGN FOR A BOTTLE OR SIMILAR ARTICLE OF MANUFACTURE

Application filed March 4, 1932. Serial No. 43,082. Term of patent 14 years.

To all whom it may concern:

Be it known that I, JOHN E. LAIRD, a citizen of the United States, and resident of Matawan, in the county of Monmouth, State of New Jersey, have invented a new, original, and ornamental Design for a Bottle or Similar Article of Manufacture.

I claim:—

An ornamental design for a bottle or similar article of manufacture, as shown.

Signed at Matawan, in the county of Monmouth, State of New Jersey, this 25 day of February, 1932.

JOHN E. LAIRD.
